CLAIM

The ornamental design for a feeding tube, as shown and described.

DESCRIPTION

FIG. 1 is a fragmentary perspective view of a feeding tube showing our new design, the tube being broken away to indicate indeterminate length;

FIG. 2 is a second fragmentary perspective view thereof, with the feeding tube inverted from the position shown in FIG. 1;

FIG. 3 is a fragmentary front elevation view thereof, it being understood that the rear elevation view is identical;

FIG. 4 is a fragmentary right side elevation view thereof, it being understood that the left side elevation view is identical;

FIG. 5 is a top view thereof; and

FIG. 6 is a bottom view thereof;

FIG. 7 is a fragmentary perspective view of a second embodiment of a feeding tube showing our new design, the tube being broken away to indicate indeterminate length;

FIG. 8 is a second fragmentary perspective view thereof, with the feeding tube inverted from the position shown in FIG. 7;

FIG. 9 is a fragmentary front elevation view thereof;

FIG. 10 is a fragmentary right side elevation view thereof, it being understood that the left side elevation view is identical;

FIG. 11 is a fragmentary rear elevation view thereof;

FIG. 12 is a top view thereof; and,

FIG. 13 is a bottom view thereof.
